UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER-MOTION FOR LOOMS.

1,331,827.

Specification of Letters Patent. Patented Feb. 24, 1920.

Application filed November 5, 1917. Serial No. 200,251.

To all whom it may concern:

Be it known that I, EDWARD S. STIMPSON, a citizen of the United States, residing at Hopedale, county of Worcester, and State of Massachusetts, have invented an Improvement in Feeler-Motions for Looms, of which the following description, in connection with the accompanying drawings, is a specification, like characters on the drawings representing like parts.

This invention relates to feeler mechanisms for looms, and more particularly to feeler mechanisms of that type wherein the change in the operative condition of the loom, such as replenishment of filling, is effected prior to complete exhaustion of the filling in the shuttle.

The present invention is a development or improvement on the feeler motions wherein the feeler motion devices are located at one side of the loom and the filling replenishing mechanism, as usual, is located at the opposite side of the loom. Under the conditions suggested, it is desirable in some instances to delay the operation of replenishment until the shuttle has been picked a plurality of times. Where the feeler motion dictates replenishment of filling as soon as the shuttle reaches the opposite or filling replenishing side of the loom, the action of parts must of necessity follow in close succession. A delay is sometimes desired in order to more efficiently and practically carry into effect the purposes of the feeler motion.

An important feature of the present invention, therefore, consists of means associated with a feeler for delaying the replenishing operation until after the shuttle has made a plurality of picks or has made two or more excursions to the filling replenishing side of the loom. This feature of the invention is carried into effect by associating with the feeler, means actuated and positioned by the detecting action of the feeler member to effect operative relation of parts and consequent initiation of filling replenishment after the shuttle has made a plurality of picks.

The above and various other features of the invention will be hereinafter described in connection with the accompanying drawing

which shows one good, practical form of means for carrying the invention into practical effect and the various novel features and combinations of parts will then be definitely set forth by the claims.

In the drawings:

Figure 1 is a plan view showing parts at the detecting side of the loom equipped with the present invention, some of the parts being broken away for clearness of illustration, and illustrating the position assumed by the feeler member on a detecting beat when a working supply of filling is present in the shuttle;

Fig. 2 is a detail, partly broken away, showing the position of the feeler and associated parts when filling is substantially exhausted on a detecting beat;

Fig. 3 is an enlarged detail, showing the actuator and operating member in the position assumed by these parts when the loom is running with a working supply of filling present in the shuttle, and also showing in broken-away detail, locking means for the controller;

Fig. 4 represents in detail side elevation, the position assumed by the parts illustrated by Fig. 3, when, on a detecting beat, the feeler member has detected substantial exhaustion of filling; and

Fig. 5 is a view similar to that of Fig. 4 showing the relation of parts when the operating member moves backwardly after a detecting action by the feeler member.

Fig. 6 is a perspective view of the controller and the parts associated therewith.

Referring to the drawings: The loom frame 1, only a portion of which is illustrated, may be of any suitable character for supporting the operating parts. Mounted on the loom frame is the transverse or rock shaft 2 supported in bearings 3 secured to the loom frame by suitable means such as the bolts 4. Extending upwardly from the transverse or rock shaft 2 is an arm 5, to the upper end of which at 6 is pivotally connected the arm 7, which for identification, may hereinafter be termed the actuator, because by engagement of the rearwardly-extending end 48 thereof, with an operating member 9 as will hereinafter more fully ap-

pear, the actuator 7 effects rocking movement of the transverse or rock shaft 2, counter-clockwise, Fig. 3, against its usual holding spring, and the operation of filling replenishment is initiated.

5 The lay carries the usual shuttle-box 10 having an opening or slot 11 in the front wall thereof, and the shuttle 12 in which is mounted the filling carrier 13 is likewise 10 provided with an opening 14 which, when the shuttle is properly positioned in the shuttle-box, registers with the opening 11 in the front wall of the latter to permit the 15 feeler member to enter the shuttle on a detecting beat and feel for the filling.

The loom frame 1 has the usual shipper stand 15 secured thereto and provided with the slot 16 in which may move the shipper handle 17, as usual. Adjustably mounted 20 on a bracket 18 which may be conveniently secured to the shipper stand 15 is the feeler stand 19. The feeler stand 19 is provided with a slot 20 by which it may be conveniently secured in adjusted position on the 25 bracket 18 by suitable means such as the bolt 21, the construction being such that the feeler stand 19 may be adjusted frontwardly and rearwardly and angularly with respect to the supporting bracket 18.

30 The feeler member in the illustrated form of the invention is supported in an inclined position relative to the longitudinal axis of the shuttle so that on a detecting beat the feeler member may be moved lengthwise on 35 its support and be given a swinging movement laterally. The rear portion of the feeler stand 19 is provided with a laterally-extending slot or guideway through which the feeler member 22 extends, and at its 40 frontward portion, the feeler stand is also provided with a guideway through which the feeler member 22 may move longitudinally and have a swinging movement. The rear guideway for the feeler member 22 is indicated at 23, being formed between upwardly-extending lugs of the feeler stand 19 and the feeler member is confined for movement lengthwise and laterally in said 45 guideway by a suitable cap-plate 24. The front guideway for the feeler member 22 may be suitably provided as indicated in Fig. 1, by means of a block or bracket 25 through which at 26 the front end portion of the feeler member 22 loosely extends.

50 Secured to the feeler member is a bridge-piece 27, the side portions of which may rest upon the feeler stand 19, and interposed between the bridgepiece 27 and the front guideway is a spring 28, the normal 55 tendency of which is to move the feeler member 22 lengthwise to its rearward position as indicated by dotted lines in Fig. 1, the construction being such that the feeler member may be moved frontwardly under 60 the impulse of the frontward pressure of the

filling in the shuttle and have lateral movement in its guideways.

Rising from the feeler stand 19 is an arm 29, Figs. 1, 2 and 6, on which is pivotally mounted at 30 the swing-piece 31 having a 70 lower wing portion 32 which is adapted at times to engage a projection 33 secured to or movable with the feeler member 22. The plane of movement of the swing-piece 31 is inclined to the longitudinal axis of the shuttle. The feeler member 22 has a filling-engaging end portion 34 provided with teeth or a roughened surface, the construction being such that when a sufficient supply of filling is present in the shuttle on a detecting beat to continue the weaving operation, the toothed or roughened end portion 34 of the feeler member by engagement with the filling, will be prevented from movement 80 longitudinally of the shuttle under the frontward pressure as the lay completes its detecting beat. Under these conditions, the part 33 carried by the feeler member will not engage the wing portion 32 of the swing member 31 as the feeler member moves 90 frontwardly in its changing angular position, as indicated by dotted and full lines in Fig. 1. When the filling has become substantially exhausted, however, the frontward pressure of the filling carrier or bobbin against the end of the feeler member will displace the feeler member laterally or in a direction longitudinally of the shuttle as indicated in Fig. 2, and upon frontward movement of the feeler member, as the lay 100 completes its detecting beat, the part 33 will engage the wing 32 of the swing member 31 and move or swing it upon its support. 95

105 Mounted in suitable bearings 35 carried by the loom frame or shipper stand is a rock shaft 36 which, for the purposes of identification, may be hereinafter termed the controller. The bearings 35 may be sustained in any suitable manner and as shown, are supported by a lug or projection 37 through which and a part 38 extends a bolt 39. Projecting from opposite sides of the part 38 are the arms 40 which may be conveniently provided as one form of means for sustaining the bearings 35 in desired position. The rock shaft or controller 36 may be held from longitudinal movement in its bearings 35 by suitable means such as the washers or collars 41. Secured to and projecting downwardly from the controller 36 is a 110 finger 42, the lower end portion 43 of which is adapted to be engaged by the wing 32 of a swing member 31, when the latter is moved by the feeler member 22 under the conditions hereinbefore described. The finger 42 and the lower portion 43 thereof may be variously contrived, and as shown in the drawing, the finger 42 is clamped to the controller 36 by a bolt 44 as indicated in Fig. 6, the construction being such that 115 120 125 130

when the finger 42 is moved by the swing member, the controller 36 will be rocked in its bearings.

The controller 36 remote from the feeler member, is provided with a crank arm 45 which underlies a spring 46 secured to the actuator 7, as best indicated in Figs. 3, 4 and 5, the crank arm 45 thus sustaining the actuator 7 through the medium of the spring 46. The spring 46 may be of any desired character and is conveniently formed as a leaf spring, one end of which may be secured by suitable means such as the screws 47 to a projection or lug 48' formed as part 10 of or secured to the actuator 7. When the parts are in normal position, that is, during the weaving operation when sufficient filling is in the shuttle, they assume the relation indicated in Fig. 3, wherein the crank arm 15 45 through the medium of the spring 46 sustains the actuator 7 in position with its rear end portion 48, Fig. 3, below the projection 49 secured to or formed as part of the operator 9, the construction being such 20 that as the operator 9, which may be a weft hammer or a part operating therewith, moves backwardly and forwardly as usual, the projection 49 of the operating member will pursue a path above the end 48 of the 25 actuator. When the filling has become substantially exhausted, however, the feeler member 22 will be laterally displaced by the forward pressure and as it moves forwardly it will turn the controller through 30 the means hereinbefore described, but just prior to such turning action of the controller, the end 49 of the operating member 9 will have ridden over the end 48 of the actuator 7, so that as the controller 36 is 35 turned by the feeler member 22, the crank arm 45 will act upwardly against the spring 46 and place the same under tension as indicated in Fig. 4.

In order to maintain or lock the controller 45 36 in position with the spring 46 under tension, and hold it in such locked position as the feeler returns to its rearward or feeling position, the present invention provides a controller lock. This lock may be variously 50 contrived, but in the present instance of the invention it comprises a spring-actuated plunger, Fig. 3, the top portion of which is preferably inclined or formed conical in shape and is adapted to coöperate with the 55 inclined portions at the lower end of the finger 42. The spring plunger in the present instance of the invention is shown as comprising a conical head portion 50 movable in a recess 51 formed in the feeler stand 19. Between the head portion 50 of the lock and the lower end of the recess is a spring 52 which normally tends to lift the head 50 into locking engagement with one or the other of the inclined surfaces 53 at 60 the lower end of the finger 42, the construc- 65 tion being such that the finger 42 will be locked yieldingly to one or the other side of the locking plunger 50, to thereby maintain the controller in the prescribed position. In order to limit the upward movement of the locking plunger, the head thereof may be provided with a screw-bolt 54 adapted to receive stop nuts 55 which may contact with the upper walls of the recessed portion of the feeler stand, substantially as indicated 70 in Fig. 3. The action of the controller lock is such that while it may hold the finger 42 with the crank arm 45 in either position indicated in Fig. 3 or the position indicated in Fig. 4, it will yield under an impulse imparted to the controller 36 and permit the finger 42 to pass the lock. When the controller 36 is turned from the position indicated in Fig. 3 to that indicated in Fig. 4, by the feeler member on a detection of substantial exhaustion of filling, the controller lock will hold the finger 42 and, perforce, the controller, in the position indicated in Fig. 4 as the feeler member returns to rearward feeling position, so that as the operating member 9 moves backward from the position indicated in Fig. 4 and frees the end 48 of the actuator 7, the tensioned spring 46 will cause the controller to lift and place its end 48 in the path of the projection 49 of the operating member 9 on its next forward movement. 80

Upon backward movement of the lay after a detection of substantial exhaustion of filling by the feeler member, the shuttle is 100 picked to the replenishing side of the loom, but inasmuch as the end 48 of the actuator 7 was below the end 49 of the operating member 9, when the latter moved forwardly as usual on the detecting beat, the 105 actuator 7 was not moved forwardly and perforce, the transverse or rock shaft 2 was not actuated and filling replenishment was not effected when the shuttle reached the replenishing side of the loom. The next beat 110 of the lay is the non-detecting beat, the shuttle being at the replenishing side of the loom, and the operating member 9 still maintaining its forward position as indicated in Fig. 4. As the lay goes back after 115 the non-detecting beat, the shuttle is picked to the detecting side of the loom and the operating member 9 has retreated, thus freeing the end 48 of the actuator 7, which thereupon assumes the position indicated in Fig. 5 under the impulse of the tensioned spring 46, so that on the next forward movement of the operating member 9, which takes place on the detecting movement of the lay, the transverse or rock shaft 2 is 120 turned and the replenishing mechanism is positioned to effect replenishment when the shuttle again or the second time reaches the replenishing side of the loom. Thus, after a 125 detection of substantial exhaustion of filling, 130

the replenishing operation is suspended or delayed while the shuttle makes a plurality of picks and in the present instance of the invention, until the shuttle makes three 5 picks, or passes to the replenishing side of the loom; then to the detecting side of the loom; and back to the replenishing side.

When an initiation of filling replenishment has been made, as hereinbefore described, it is desirable to unlock the controller 36 and return it to its normal position ready for the next detecting action of the feeler member. This is effected by turning the controller 36 so as to swing the toe 10 15 42 backwardly toward the swing member 31. Various means may be devised for accomplishing this purpose, but in the present instance of the invention the actuator 7 is provided with an incline or cam portion 56, Figs. 3, 4 and 5, which, as the actuator is moved frontwardly by the operating member 9 to initiate replenishment of filling, engages the crank arm 45 of the controller and causes it to be moved downwardly, or contraclockwise, Fig. 5, to throw the finger 42 past the lock 50 into its initial position as indicated in Fig. 3. The parts are then in normal position, ready for another cycle of replenishing operations.

30 The feeler member 22 should be returned to its initial feeling position after each detecting beat and also after each replenishing operation. This is effected by means of a cam or incline 57 formed on the feeler stand 35 19 which is adapted to engage a projection on the feeler member to move it laterally into feeling position as it is moved rearwardly by its spring 28.

As the actuator 7 is moved frontwardly by 40 the operating member 9, the end 48 of the actuator engages the recessed portion 58 in the head of the operating member 9 and as the cam 56 of the actuator rides over the crank arm 45 of the controller, the actuator 45 is prevented from any undue lifting movement.

Changes may suggest themselves in the details of the described invention, but the drawings indicate a good, practical form 50 thereof to which, however, the claims are not necessarily restricted.

What is claimed is:—

1. In a loom, the combination of a feeler member, means for supporting the feeler member to feel for the filling in the shuttle at the side of the loom opposite the replenishing position, an actuator, an operating member, a controller between the feeler member and actuator, and means for locking 55 the controller in position upon detection of substantial exhaustion of filling to effect operative relation of the actuator and operating member when the shuttle returns a second time to the filling replenishing position.

2. In a feeler mechanism for looms, the combination of a feeler member to enter the shuttle and indicate the condition of the filling therein, means actuated by the feeler member when it indicates substantial exhaustion of filling, a spring placed under tension by said means when actuated by the feeler member upon substantial exhaustion of filling, and means actuated by the tensioned spring for positioning the parts for initiating replenishment of filling when the shuttle returns a second time to the filling replenishing side of the loom after an indication of substantial exhaustion of filling by the feeler member. 70 75 80

3. In a feeler mechanism for looms, the combination of a feeler member for detecting the condition of filling in the shuttle on each detecting beat, an actuator and operating member, a controller moved from a normal to a secondary position by the feeler member when it detects substantial exhaustion of filling, a lock for locking the controller in the secondary position to which it has been moved by the feeler member, and means between the controller and actuator for operatively relating the actuator and operating member while the controller is locked in its secondary position. 85 90

4. In a feeler mechanism for looms, the combination of a feeler member for detecting the condition of filling in the shuttle on each detecting beat, a controller moved from a normal to a secondary position by the feeler member when it detects substantial exhaustion of filling in the shuttle, a lock for locking the controller in the secondary position to which it has been moved by the feeler member upon detection of substantial exhaustion of filling, an actuator and operating member, means between the controller and actuator for operatively relating the actuator and operating member, and means for unlocking the controller and returning it to initial position. 95 100 105 110

5. In a feeler mechanism for looms, the combination of a feeler member to detect the condition of filling in the shuttle, an actuator, an operating member for moving the actuator, a rock shaft between the feeler member and actuator adapted to be rocked by the feeler when it detects substantial exhaustion of filling, a spring between the rock shaft and actuator placed under tension by the rock shaft when rocked by the feeler 115 and acting under the induced tension to operatively relate the actuator and operating member when the shuttle returns a second time to the replenishing side of the loom after an indication of substantial exhaustion of filling. 120 125

6. In a feeler mechanism for looms, the combination of a feeler member to detect the condition of filling in the shuttle, an actuator, an operating member for moving the 130

- actuator, a rock shaft between the feeler member and actuator adapted to be rocked by the feeler when it detects substantial exhaustion of filling, a lock for locking the 5 rock shaft in the position to which it has been moved by the feeler member, a spring between the rock shaft and actuator placed under tension by the rock shaft when rocked by the feeler and acting under the 10 induced tension to operatively relate the actuator and operating member when the shuttle returns a second time to the replenishing side of the loom after an indication of substantial exhaustion of filling.
- 15 7. In a feeler mechanism for looms, the combination of a feeler member, an actuator, an operating member, a controller extending between the feeler member and actuator, a spring between the controller and actuator 20 which is placed under tension by the controller when moved by the feeler on indication of substantial exhaustion of filling and acting by the induced tension to operatively
- relate the actuator and operating member when the shuttle has made a plural number 25 of picks after indication of substantial exhaustion of filling, and means moved by the actuator for returning the controller to normal position.
8. In a feeler mechanism for looms, the 30 combination of a feeler member, an actuator, an operating member for moving the actuator, a controller between the feeler member and actuator, a spring between the controller and actuator placed under tension by the controller when moved by the 35 feeler member to operatively relate the actuator and operating member when the shuttle has made a plural number of picks after a call for replenishment of filling, and 40 a cam moved by the actuator for resetting the controller.

In testimony whereof I have signed my name to this specification.

EDWARD S. STIMPSON.
